UNITED STATES PATENT OFFICE.

CHARLES FREBORG, OF KANKAKEE, ILLINOIS. ASSIGNOR TO PRICE AND TEEPLE PIANO COMPANY, OF CHICAGO, ILLINOIS, A CORPORATION OF ILLINOIS.

AUTOMATIC MUSICAL INSTRUMENT.

1,127,426.

Specification of Letters Patent.

Patented Feb. 9, 1915.

Application filed March 1, 1913. Serial No. 751,440.

To all whom it may concern:

Be it known that I, CHARLES FREBORG, a citizen of the United States, residing at Kankakee, in the county of Kankakee and State of Illinois, have invented certain new and useful Improvements in Automatic Musical Instruments, of which the following is a specification.

The principal object of my invention is to provide a new and improved adjustable tracker board for automatic musical instruments such as employ perforated paper music sheets.

Another object of my invention is to provide an adjustable tracker board by which a musical selection can be played as desired in a transposed higher or lower key.

A further object of my invention is to provide means for slightly adjusting the tracker board of such a musical instrument so that if the music roll runs a little to one side or the other the tracker board can be shifted to follow it.

All these objects of my invention and others will be made apparent in the following specification and claims, taken in connection with the accompanying drawings. In these drawings I have illustrated one specific embodiment of my invention for the purpose of making a clear and definite explanation, but it will be understood that the invention is defined in the appended claims.

Referring to the drawings Figure 1 is a front elevation of a tracker board embodying my improvement. Fig. 2 is a top plan view thereof. Figs. 3 and 4 are end elevations of the tracker board adjusting mechanism showing it in two different positions. Fig. 5 is a vertical section taken on the line 5, 5 of Fig. 3 looking in the direction of the arrows. Fig. 6 is a vertical section across the tracker board taken on the line 6, 6 of Fig. 2 looking in the direction of the arrows. Fig. 7 is a perspective view showing a detail.

A rectangular wooden frame is formed of the top member 15, bottom member 16 and two side members 17. These side members 17 support the music roll 18 above and the winding roll 19 below and the perforated music sheet in normal operation will unwind from the roll 18 and wind upon the roll 19.

The metal brackets 20 are attached to the rear sides of the respective vertical frame members 17, as shown in Fig. 7, and their extremities 21 are bent forward and notched at 22 so as to form guides for the tracker board 23, which has inturned lips 24 engaging the notches 22.

The wooden blocks 25 are secured by the screws 26 to the inner faces of the metal brackets 21 and form ledges to which the boards 27 and 28 may be secured. The frame is inclosed on the rear side by the boards 30 and 29 behind the rolls 18 and 19, respectively.

The holes in the tracker board are designated 31. From each such hole 31 there extends a short metal tube 32, as shown in Fig. 6, the tubes 32 being staggered so as to give room for attaching the rubber tubes 33. These rubber tubes 33 extend to the exhaust air chamber and are connected in such a way that inrush of air through the holes 31 actuates the playing mechanism.

The sleeve 34 is secured in the extremity of the left-hand bracket 21 and has a steep internal thread 35 which is engaged by the corresponding thread 37 on the screw plug 36. This plug 36 has rigidly attached thereto a depending arm 38 carrying a handle 39 at its lower extremity. Beyond the arm 38 is also rigidly attached to the plug 36 a head 40 and between the head 40 and the arm 38 is rotatably mounted a dog 41 with an upwardly projecting handle 43. The adjacent edge of the tracker board 23 has a row of notches 44 spaced apart the same distance as the distance between successive holes 31 in the tracker board. The dog 41 has a part 42 adapted to enter one of these notches 44. The dog 41 also has a forwardly projecting pointer 45 adapted to register with the arrow 46 marked on the tracker board. Beside this arrow 46 there are other marks each, like the arrow 46, in registry with a particular notch 44. The dog 41 carries a leaf spring 48, the free end of which presses against the tracker board at a point below the plug 36, thus tending to rotate the dog 41 in a direction to cause its part 42 to engage a notch 44 in the tracker board.

For normal operation of the device the pointer 45 is set opposite the arrow 46, but should it be desired to play a musical selec-

tion in a higher or lower key this may be accomplished by pushing back the dog 41 by pressing a thumb or finger against the handle 43, and then shifting the tracker board 23 manually to the right or left, after which the tracker board may be locked in a definite proper position by releasing the dog 41 and permitting the spring 48 to throw it in engagement with one of the notches 44. By means of the scale 47 and pointer 45 it can easily be determined how much the playing of the selection is transposed. Should it be desired while a selection is being played to shift the tracker board slightly, as for example if the music roll was not registering quite accurately with the tracker board, this can be accomplished by means of the handle 39. A slight movement of the handle 39 will rotate the shaft 36 and thereby shift the tracker board 23 to any desired extent within limits that may be desired. Thus if the edges of the music roll become worn with use so that the holes in the sheet do not register accurately with the holes 31 in the tracker board 23, the tracker board can be shifted during the playing of the selection to effect perfect registry. The shaft 36, attached handle 38, and dog 41 can be readily removed by disengaging the dog 41, as shown in Fig. 4, and moving the tracker board 23 to the extreme right. In this way the end of the tracker board 23 will clear the leaf spring 48 and permit the stud 36 to be unscrewed from the sleeve 34.

It will be seen that I have provided a simple and effective device by means of which the tracker board can be shifted definitely so as to play a selection in a transposed key when desired and by means of which during the playing of a selection perfect registry of the perforations in the tracker board with those in the music sheet can be obtained if necessary.

45 I claim:

1. In a device of the class described, a displaceable tracker board, means to latch the same at certain definite positions spaced by suitable intervals for transposing, said 50 means comprising a notched member and a dog to engage a notch thereof, and means to adjust the tracker board by a continuous movement over a narrow range while in normal operation.

55 2. In a device of the class described, a displaceable tracker board, guiding means to constrain its movement in a longitudinal direction, a latch engaging the tracker board, a series of places on the tracker 60 board adapted to be engaged by said latch, the spacing of said places being at definite intervals adapted for transposing, means to displace the latch and the tracker board therewith over a narrow range gradually 65 while the device is in normal operation.

3. In a device of the class described, a tracker board mounted so as to be displaceable longitudinally and having a series of notches therein, a pivoted dog adapted to engage one of said notches, and means 70 to displace the pivotal mounting of the dog in a direction parallel to the direction of displacement of the tracker board.

4. In a device of the class described, a displaceable tracker board, means to constrain its movement in a longitudinal direction, said tracker board having a series of notches therein, a screw-threaded shaft with its axis parallel to the length of the tracker board, a dog pivoted on said shaft 75 and adapted to engage one of the said notches in the tracker board, and a handle to rotate the said shaft and thereby displace the dog longitudinally and with it the tracker board.

80 5. In a device of the class described, a tracker board, supports therefor adjacent to the ends thereof, an internally screw-threaded sleeve carried by one of said supports, an externally screw-threaded shaft 90 engaging said sleeve, a dog carried by said shaft, said tracker board having notches therein adapted to be engaged by said dog, and a handle to rotate said shaft and thereby displace the dog longitudinally and with 95 it the tracker board.

6. In a device of the class described, a tracker board and a support therefor, said tracker board being longitudinally displaceable with relation to said support, means 100 carried by said support to engage said tracker board and hold the same at definite points of adjustment, and means to effect added adjustment of said tracker board when engaged by said first named means to enable the obtaining of accurate registry on said tracker board of a perforated music sheet.

7. In a device of the class described, a tracker board, a support therefor, said tracker board being longitudinally displaceable upon said support, a latch carried by the support engaging the tracker board, said latch being displaceable in a direction parallel to the tracker board, and a plurality of definite places on said tracker board adapted to be engaged by said latch.

110 8. In a device of the class described, a rectangular frame, brackets attached to its side members on the rear faces thereof, said brackets extending inwardly and then forwardly through the frame, and a longitudinally displaceable tracker board supported on the ends of said brackets.

115 9. In a device of the class described, a frame, two brackets attached to the back of the frame on opposite sides and extending a limited distance toward each other, said brackets having their ends bent forward and extending parallel to each other into 120

125

130

the frame, and having their extreme ends notched, and a tracker board with guide lips engaging the notches in the ends of said brackets.

10. In a device of the class described, a rectangular frame, a tracker board, and brackets carried by the frame and supporting the tracker board, each said bracket consisting of a metal plate bent at a right angle and having one end attached to the side member of the frame and the other end extending forwardly within the frame.

11. In a device of the class described, a frame, brackets each bent at a right angle and attached to the sides of the frame and extending thence within the frame, blocks attached to the inner faces of said brackets so as to form ledges, inclosing boards attached to said ledges, and a tracker board 20 displaceably mounted on the extremities of the brackets.

12. In a device of the class described, a frame, brackets attached on the back thereof and extending thence forward through the frame, a screw-threaded sleeve carried by one of said brackets, a tracker board slidably mounted on the ends of both brackets, a screw-threaded shaft engaging said screw-threaded sleeve, and adjustable

latching means carried by said shaft and 30 engaging the tracker board.

13. In a device of the class described, a tracker board, a support therefor, said tracker board being longitudinally adjustable on said support, means to secure the 35 tracker board at definitely spaced positions for transposing, and means to effect an added adjustment of said tracker board in normal operation to accurately register with a perforated music sheet.

14. In a device of the class described, a displaceable tracker board, means to latch the same at certain definite positions spaced by suitable intervals for transposing, said means comprising a notched member and a 45 dog to engage a notch thereof, and means to adjust the tracker board by a continuous movement over a narrow range while in normal operation, said last mentioned means being connected to the said dog, and acting 50 therethrough upon the tracker board.

In testimony whereof, I have subscribed my name.

CHARLES FREBORG.
